UNITED STATES PATENT OFFICE.

DANIEL M. COOPER, OF ROCHESTER, NEW YORK, ASSIGNOR TO THE AMERICAN LAUNDRY MACHINERY COMPANY, OF CINCINNATI, OHIO, A CORPORATION OF OHIO.

GARMENT-HANGER.

1,087,159.

Specification of Letters Patent. Patented Feb. 17, 1914.

Application filed July 28, 1911. Serial No. 641,059.

To all whom it may concern:

Be it known that I, DANIEL M. COOPER, of Rochester, in the county of Monroe and State of New York, have invented certain new and useful Improvements in Garment-Hangers; and I do hereby declare the following to be a full, clear, and exact description of the same, reference being had to the accompanying drawings, forming a part of this specification, and to the reference-numerals marked thereon.

My present invention relates to improvements in garment hangers, and more particularly to the type shown in Letters Patent No. 15 822,604, granted June 5, 1906 to Arthur T. Hagen covering a clothes drier for use in connection with drying apparatus for laundries, and it has for its object the provision of a novel form and arrangement of parts 20 whereby the articles may be gripped or held more securely, and readily released.

A further object of the invention is to provide a construction which will enable the parts to be more readily assembled and to be manufactured at a comparatively lower 25 cost.

To these and other ends the invention consists in certain improvements and combinations of parts all as will be hereinafter more 30 fully described, the novel features being pointed out in the claims at the end of the specification.

In the drawings: Figure 1 is a view in side elevation, illustrating one embodiment 35 of the invention; Fig. 2 is a longitudinal vertical section taken through Fig. 1, with the upper part of the support broken away; Fig. 3 is a transverse sectional view on the line $x-x$ of Fig. 1; Fig. 4 is a similar view 40 on the line $y-y$ of Fig. 1; Fig. 5 is a vertical sectional view on the line $a-a$ of Fig. 1; Fig. 6 is a similar view on the line $b-b$ of Fig. 1, and Fig. 7 is a similar view on the line $c-c$ of Fig. 1.

Similar reference numerals throughout the several figures indicate the same parts.

In the present application, I have disclosed my invention in a preferred embodiment, as applied to a clothes hanger for use 50 in connection with laundry drying apparatus of the endless conveyer type, the same, in the present instance, including a support 1 provided at its lower end with a yoke 2,

within which the arms carrying the gripping members or jaws are pivotally arranged.

The hanger is preferably provided with two pairs of pivoted arms, and for convenience in the present application I will describe one of these pairs and its coöperating parts. The arms are designated at 3 and 4, respectively, and are formed from blanks of sheet metal, these being cut and shaped to effect the desired conformation of the arms, which are preferably substantially U-shaped in cross section and provided on their adjacent open edges with inwardly extending flanges 5 for a purpose now to be described. The arms 3 and 4 are pivoted to the yoke 2 below and above each other, respectively, so as to obtain relative sliding movement between them coincident with their swinging movement, and to this end, in the present embodiment, the lower arm 3 is provided with upwardly and outwardly extending 65 projecting portions 6 which extend between the flanges 5 on the upper arm and are adapted to engage the upper side of said flanges, as shown in Fig. 7, whereby parallel movement of the arms is effected.

The upper arm 4 is provided with a downwardly extending portion 7 which co-operates with the outer extremity of the arm 3 to grip the article therebetween, and in order that the clothes may be more securely held, and further, that they may not be damaged by contact, while wet, with metallic parts, I provide detachable gripping members or jaws, formed preferably of some vitreous material, such as glass, and adapted to be held by the pivoted arms. To this end, in the present embodiment jaws 8 are provided having engaging faces which are preferably convex and corrugated to secure a more effective grip on the article to be held. The jaws 8 have reduced portions for engagement with the flanges 5 of the arms, and lugs 9 are arranged in the rear of said reduced portions, as shown clearly in Figs. 2 and 4, so as to hold the jaws in their proper positions, and prevent accidental removal. Suitable adjusting screws and nuts are provided for holding the arms and jaws in their proper coöperative positions, and the jaws may be removed by loosening the attaching screws sufficiently to

release them, it being necessary to separate the walls slightly, to remove the jaws from the upper arms.

By constructing the arms of sheet metal, 5 as herein shown and described, I am able to produce a hanger of much lighter weight, and at a smaller comparative cost than heretofore. And by the provision of the gripping members or jaws, as set forth, 10 it is possible to hold the articles more securely and without subjecting them to the undesirable effects attendant upon the use of metallic jaws, and in case of breakage of the jaws, they may readily be replaced without 15 difficulty.

I claim as my invention:

1. In a hanger, the combination with a support, of arms formed of sheet metal pivoted one above the other on different centers 20 on the support, said arms being substantially U-shaped in cross section and having inwardly extending flanges at their open edges, and coöperating jaws removably secured to the arms and held in position by 25 said flanges.

2. In a hanger, the combination with a support, of arms formed of sheet metal pivoted one above the other on different cen-

ters on the support, said arms being substantially U-shaped in cross section and having inwardly extending flanges at their open edges, extensions formed on the lower arm and extending between and over the flanges on the upper arm, and coöperating jaws secured to the arms and held in position by the flanges.

3. In a hanger, the combination with a support, of arms formed of sheet metal pivoted one above the other on different centers on the support, said arms being substantially U-shaped in cross section and having inwardly extending flanges at their open edges, and coöperating jaws provided with lugs adapted to engage the flanges on the arms.

4. A hanger comprising a support, arms formed integrally of sheet metal and pivoted one above the other on different centers on the support, said arms being substantially U-shaped in cross section, and coöperating jaws removably secured between the walls of the arms.

DANIEL M. COOPER.
